CARBON PILE ARMATURE ASSEMBLY

Carl O. Bathgate, Rumson, N. J., assignor to Bendix Aviation Corporation, Teterboro, N. J., a corporation of Delaware

Application October 3, 1951, Serial No. 249,523

8 Claims. (Cl. 201—51)

The present invention relates to carbon pile regulators and more particularly to the armature assembly for a carbon pile regulator.

Carbon pile regulators have come into general use for such purposes as controlling the voltage, current and frequency of generators. These carbon pile regulators operate on the principle of varying the pressure applied to the carbon pile. One end of the pile is relatively fixed. Operatively associated with the other end to apply pressure on the pile is an armature carried by a diaphragm type spring which tends to urge the armature towards the pile. An electromagnet, when energized, tends to withdraw the armature from the pile against the bias of the diaphragm spring. For proper operation, it is necessary for the electromagnetic force acting upon the armature to match the spring characteristics as the air gap varies. Heretofore in order to adjust the air gap it has been necessary to disassemble the regulator, remove the armature assembly, and make the necessary armature adjustment by removing or adding shims between the armature and diaphragm. At best this is a lengthy operation and is not satisfactory from the production standpoint.

In the present invention, an armature assembly is provided that can be readily adjusted without removing the whole armature assembly. The adjustment is made from the outside of the regulator and the only disassembly required is the removal of the core of the electromagnet.

It is an object of the invention to provide an adjustable armature assembly for a carbon pile regulator.

Another object of the invention is to provide an improved carbon pile regulator.

Another object of the invention is to provide an armature assembly for a carbon pile regulator which may be adjusted in the regulator.

Another object of the invention is to provide simple means for adjusting the air gap in a carbon pile regulator.

The above and other objects and features of the invention will appear more fully hereinafter from a consideration of the following description taken in connection with the accompanying drawing wherein one embodiment of the invention is illustrated by way of example.

In the drawing:

Figure 1 is a cross-sectional view of the electromagnet and armature section of a carbon pile regulator illustrating one embodiment of the invention.

Figure 2 is an end view of the armature of Figure 1.

Figure 3 is a partial cross-sectional view of the electromagnet and armature section of a carbon pile regulator illustrating another embodiment of the invention.

Figure 4 is an end view of the armature of Figure 3.

In the drawing similar parts in the various figures have been assigned the same reference numerals.

Referring now to Figure 1, a carbon pile regulator is indicated generally by the numeral 5, only that portion of the regulator housing the electromagnet and armature is illustrated. It is understood, however, that it will include the carbon pile, housing and cooling fins. The regulator 5 has a bottom plate 6 on which is mounted a housing 7. The plate 6 and housing 7 are formed of a suitable ferromagnetic material. A core 8 of similar ferromagnetic material is screw threaded to the plate 6 and projects into an electromagnet winding 9 positioned within the housing 7 between the plate 6 and a flange 10 extending inward and forming the pole face for the electromagnet assembly.

An armature assembly 11 is positioned in the housing 7 and has a diaphragm type spring 12 seated on an annular member 13. An armature plate 14 is positioned on the side of the spring 12 adjacent to the core 8. At the opposite side of the spring 12 there is positioned a clamping plate 15 and the spring 12 is clamped between the plates 14 and 15 by suitable fastening screws 16. A cup-shaped member 17 adapted to hold a contact member 18 is mounted on the plate 15. An insulating member 19 insulates the member 17 from the plate 15. A suitable terminal 17A extends from the member 17. The contact member 18 is adapted to engage a carbon pile (not shown).

The armature plate 14 has a fixed member 20 and a movable member 21. The fixed member 20 has a hub-like projection 22 having external threads adapted to extend through and engage mating threads on the member 21. The hub 22 has a threaded counterbore portion 23 having sloping walls 24 around the mouth thereof. The hub 22 has a plurality of longitudinal slits 25 (see Figure 2). A tapered screw 26 cooperates with the sloping walls 24 to lock the members 20 and 21 together. A pair of holes 27 are provided in the member 21 to receive a wrench or tool.

In operation, in order to adjust the air gap between the member 21 and the pole piece 10, the core 8 is removed and a tool inserted to loosen the screw 26. After the screw 26 is loosened, the member 21 is rotated by means of a spanner wrench or the like, inserted in the holes 27, to move the member 21 towards or away from the member 10 as desired. Upon the desired adjustment being made, the screw 26 is tightened to lock the members 20 and 21 together. A tool may be inserted to cooperate with the slots 25 to prevent the armature assembly from turning when the adjustment is being made.

Referring now to Figures 3 and 4 wherein another embodiment of the invention is illustrated. An armature assembly is indicated generally by the numeral 30 and has a diaphragm type spring 12 seated on the member 10 of the housing 7. Inasmuch as the housing 7, core 8 and electromagnet 9 are similar to the respective parts in Figure 1, a detail description of those parts will be omitted.

An armature plate 31 is positioned on the side of the spring 12 adjacent the core 8. On the opposite side of the spring 12, a clamping plate 32 is positioned so that the spring 12 is clamped between the plates 31 and 32 by suitable fastening screws 33. A cup-shaped member 30 17 adapted to hold a contact member 18 is mounted on the plate 32 by screws 34. An insulating member 35 insulates the member 17 from the plate 32.

The armature plate 31 comprises a ring-like section 36 secured by the screws 33 and a center section 37. The sections 36 and 37 are adapted to be screw threaded together. The section 37 has an opening 38 and a pair of holes 39 adapted to receive a spanner wrench or tool (not shown). A spring washer 40 is positioned between the member 37 and the spring 12 to lock the member 37 against movement by vibration or the like. The spring 12 has an opening 41 in alignment with the opening 38. The plate 32 has a slot 42 opposite the openings 38 adapted to receive a screw driver or similar tool (not shown) whereby the armature assembly 30 can be prevented from turning while an adjustment is being made.

In operation in order to adjust the air gap between the armature plate 31 and the pole piece 10, the core 8 is removed and the armature assembly is prevented from turning by a screw driver or other tool being inserted in the slot 42 and held. A spanner wrench or other suitable tool is inserted in the holes 39 and the section 37 rotated in the desired direction relative to the ring 36. This moves the section 37 towards or away, depending upon the direction rotated, from the pole piece 10 thus changing the air gap and the curve of the electromagnet. The member 37 should extend beyond the opening in the pole piece 10 for proper operation.

Although only two embodiments of the invention have been illustrated and described, various changes in the form and relative arrangement of the parts, which will

now appear to those skilled in the art, may be made without departing from the scope of the invention.

What is claimed is:

1. In a regulator of the class including a carbon pile, a solenoid having an essentially non-linear magnetic force characteristic, said solenoid including a pole piece and an armature having an air gap therebetween, a removable core, said armature having an adjustable member, means for holding said armature to permit actuation of said adjustable means for varying said air gap, said last means being in register with said removable core.

2. In an electric regulator including a variable resistance element, an electromagnet having an essentially non-linear magnetic force characteristic and including a fixed pole piece, a winding, a removable core, and an armature, spring means supported by said pole piece and carrying said armature, said spring being adapted to oppose the magnetic force of said electromagnet, said armature having a part fixedly attached to said spring and another part screw-threaded to said fixed part and adapted for rotation and axial movement relative thereto, said last mentioned part having means in line with said movable core and accessible for adjustment upon removal of said core whereby the magnetic force characteristic of said electromagnet may be changed without disassembly of said regulator.

3. In an electric regulator including a variable resistance element, an armature having means engaging one end of said element to apply pressure thereon, a spring carrying said armature, an electromagnet supporting said spring, a core included as a part of said electromagnet and being readily removable therefrom, said armature having a part fixedly attached to said spring and another part screw-threaded to said first part for rotation with and axial movement relative thereto, said screw-threaded part having openings therein opposite said core and adapted to receive a tool insertable upon the removal of said core whereby said screw-threaded part may be rotated relative to said fixed part.

4. For use in a regulator having a variable resistance element and an electromagnet for controlling said element, an armature assembly comprising a spring member, a backing plate, a fixed armature plate, means for clamping said spring between said backing plate and said fixed armature plate, said fixed armature plate having a threaded hub extending therefrom, a movable armature plate having a threaded portion adapted to cooperate with said threaded hub for screw-threadedly mounting said movable plate to said fixed plate, and locking means for holding said members relative to each other.

5. For use in a regulator having a variable resist-

ance element and an electromagnet, an armature assembly comprising a spring member, an armature backing plate, an armature ring member, means for clamping said spring member between said backing plate and said ring member, and an adjustable armature member screw-threaded to said ring member for rotation and axial movement relative thereto.

6. For use in a carbon pile regulator having an electromagnet associated therewith, an armature assembly for said electromagnet comprising a spring member, a first armature member, means for securing said first armature member to said spring, a second armature member, means including a threaded connection for mounting said second armature member to said first armature member to permit adjustment of said second member relative to said first member and locking means for maintaining said members in a predetermined relationship.

7. In an electric regulator including a variable resistance element, an electromagnet having an essentially non-linear magnetic force characteristic and including a fixed pole piece having a cylindrical opening therein, a winding disposed in magnetic relationship with said pole piece, a removable core extending through said winding and concentric with the opening in said pole piece, an armature, spring means supported by said pole piece and carrying said armature, said spring being adapted to oppose the magnetic force of said electromagnet, said armature having a first part fixedly attached to said spring and second part screw-threaded to said first part and adapted for rotation and axial movement relative thereto, said second part being concentric with said cylindrical opening and extending over a portion of said pole piece, and means accessible through said cylindrical opening for rotating said second part relative to said first part.

8. A method of adjusting the air gap of an electromagnet in a carbon pile regulator having an armature assembly in which one section of the armature is fixedly attached to the regulator spring and another section is screw-threadedly attached to said fixed section, comprising removing the core from said electromagnet, inserting a tool in the opening left by the removal of said core to hold said spring and fixed section while rotating said screw-threaded portion.
